CLAIM

The ornamental design for a case for a mobile electronic communications device, as shown and described.

DESCRIPTION

FIG. 1 is a front, left-side, and bottom perspective view of a case for a mobile electronic communications device according to a first embodiment of our new design; FIG. 2 is a rear, right-side, and bottom perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is a front, left-side, and bottom perspective view of a case for a mobile electronic communications device according to a second embodiment of our new design;

FIG. 10 is a rear, right-side, and bottom perspective view thereof;

FIG. 11 is a front elevational view thereof;

FIG. 12 is a rear elevational view thereof;

FIG. 13 is a right side view thereof;

FIG. 14 is a left side view thereof;

FIG. 15 is a top plan view thereof; and,

FIG. 16 is a bottom plan view thereof.

The areas of textural pattern illustrated in the drawing figures of embodiment 1 represent a textural pattern that covers the entirety of the exterior surface of the case in this embodiment except for the surface of the upper side button. The contrast shown in drawing FIGS. 9-16 is part of the claimed design of embodiment 2.
